CLAIM

The ornamental design for a gun sight, as shown and described.

DESCRIPTION

FIG. 1 is a front, top, right perspective view of a gun sight of our new design;
FIG. 2 is a rear, top, left perspective view thereof;
FIG. 3 is a rear, bottom, left perspective view thereof;
FIG. 4 is a front view thereof;
FIG. 5 is a rear view thereof;
FIG. 6 is a left view thereof;
FIG. 7 is a right view thereof;
FIG. 8 is a top view thereof; and,
FIG. 9 is a bottom view thereof.

Broken lines of equal length (e.g., dash-dot) and the unshaded areas adjacent to them represent portions of the gun sight and form no part of the claimed design. Broken lines of unequal length (e.g., dash-dot) define bounds of the claimed subject matter and form no part of the claimed design. Break lines having a jagged element illustrated using broken lines form no part of the claimed design. The appearance of any portion between the break lines forms no part of the claimed design.
